CLAIM

The ornamental design for an orbital buffer, substantially as shown and described.

DESCRIPTION

FIG. 1 is a top, front and left side perspective view of an orbital buffer showing my new design;

FIG. 2 is a top plan view thereof;

FIG. 3 is a rear elevational view thereof; and

FIG. 4 is a right side elevational view thereof.

*FIG. 1.**FIG. 2.**FIG. 3.**FIG. 4.*
